James E. P. Dillon INVENTOR

BY

A. G. Burns ATTORNEY

UNITED STATES PATENT OFFICE.

JAMES E. P. DILLON, OF SOUTH BEND, INDIANA.

TRASH RECEPTACLE.

Application filed October 4, 1926. Serial No. 139,300.

This invention relates to improvements in trash receptacles of that type ordinarily stationed at street corners for the disposal of waste paper and discards from pedestrians. The object of the improvement is to afford a receptacle so constructed as to admit of easy ingress of the materials deposited, while preventing unauthorized removal of deposited matter. Another object is to provide a guarded receiving means for the receptacle through which material may be deposited and the withdrawal there through prevented.

These objects are accomplished by the construction illustrated in the accompanying drawings, in which:

Fig. 1 is an elevation in central section of a construction embodying the invention; and

Fig. 2 is a fragmentary front elevation showing the upper portion of the receptacle.

The characters of reference appearing in the description refer to parts shown in the drawings and designated thereon by corresponding characters.

The invention comprises a receptacle in the form of a box 1 supported upon legs 2 and having a cover 3 permanently fixed thereon. The front and back faces 4 and 5 of the cover slant inwardly and each has therein an opening 6, in which is disposed a hinged movable member 7, there being hinges 8 at the lower end of said member upon which said member swings. Each of said members 7 has at its lower end an inwardly extending shelf 9, and at each side a contiguous plate 10, so that the movable member 7, together with the shelf 9 and side plates 10, form a pocket.

At the upper end of each opening 6, in the cover 3, is hinged a flap 11, the hinges for which are indicated by 12, each flap being provided with a stop 13, at its upper end, that comes into contact with the cover 3 as the flap is swung inwardly, and thereby limits the inward swing of the flap. Each flap depends from its hinges with its lower end above the shelf 9 of the corresponding pocket, so that when said pocket is moved to open position, the flap becomes engaged by the shelf and is drawn into closing relation with the corresponding opening 6 in the cover and ingress to the receptacle through said

opening, while the pocket is swung outwardly, is thereby prevented.

In the lower part of the receptacle is provided a door 14 hinged on its lower end as indicated by 15, there being a staple 16 in connection with the box and extending through the door when closed, in which staple is applied a lock 17 for securing the door.

In utilizing the invention the receptacle is positioned at a convenient place on the street, and those having waste material to dispose of may deposit the same in the receptacle by swinging one of the pockets to open position and placing the waste material therein, and by subsequently moving the pocket to closed position, whereupon the corresponding flap 11 is swung inwardly by the pressure of the waste material against it, and when the flap is thus moved inwardly the material falls off the shelf into the box.

By the construction herein set forth, removal or scattering of waste material from the receptacle by irresponsible persons is prevented.

What I claim is:

1. A trash receptacle comprising a box 80 having a permanent cover the front and back faces of which slant inwardly, there being an opening in said front and back; a movable pocket member for closing each of said openings and having hinged support at its lower end so as to swing outwardly; and a flap hinged at its upper end at the top of each opening and extending into the corresponding pocket member so that said opening is closed by said flap when the corresponding pocket member is in open position, each flap having a stop thereon operable to limit inward swinging movement of the flap by contacting with the top of the said cover; and a lock controlled door for the box in the lower part thereof.

2. In a trash receptacle, a box having a permanent cover thereon and a receiving opening, a pocket member hinged at the lower end of said opening, for closing said opening; a flap having hinged support at the upper end of the opening and with its lower end extending into said pocket whereby the flap is moved into closing relation with the opening when the pocket is swung to open position, said flap having limited swinging

movement when the pocket is closed; and a lock controlled door for said box.

3. A trash receptacle including a box having a permanent cover thereon, provided with a receiving opening therein, a pocket hinged on the cover in said opening and operable to close the opening, and a flap hinged

in the cover at a point opposite the hinge connection of the pocket respecting the opening and being actuated by the pocket and 10 operable to close said opening when the pocket is moved to open position.

In testimony whereof I affix my signature.
JAMES E. P. DILLON.
